PICTURE MOUNT AND METHOD OF
MAKING THE SAME

Carroll N. Cross, Middleboro, Mass.

Application December 31, 1940, Serial No. 372,514

16 Claims. (Cl. 40—158)

This invention relates to mounts for photographs or like sheets, and the object is to provide an improved construction which, while cheap to produce, is attractive in appearance, capable of wide variation in form and which will serve to position the picture securely.

My invention will be well understood by reference to the following description taken in connection with the accompanying drawing, wherein—

Fig. 1 is a front elevation of a picture mount illustrative of the invention;

Fig. 2 is a central vertical section therethrough;

Fig. 2a is a transverse horizontal section therethrough;

Fig. 3 is a more or less diagrammatic view, partly broken away, showing a preferred method of making mounts such as are illustrated in Fig. 1;

Fig. 4 is a central vertical section through a modified construction;

Fig. 5 is a view similar to Fig. 3 showing another method of manufacture and applicable to such a structure as seen in Fig. 4 although the device illustrated in Fig. 5 is slightly different in proportion;

Fig. 6 is a vertical section on line 6—6 of Fig. 5; and

Fig. 7 is a rear view of one of the mounts as produced by the proceeding illustrated in Fig. 5.

It will be understood that in the sectional views, Figs. 2, 2a, 4 and 6, the proportion and relative thickness of the various parts which go to make up the structure are necessarily distorted to permit their being clearly shown in a drawing of this nature.

For convenience in the following description and in the appended claims I will use the word "board" to refer to material which, although thin, is of some thickness and stiffness as exemplified, for instance, by cardboard or binder's board and as contrasted with paper, cloth or the like which is freely flexible and more or less limp and which I shall refer to as sheet material.

In the construction of frame-like mounts for unmounted photographs or like thin display sheets, to prevent the photograph from slipping out of alignment with the frame it has been usual to provide as a part of the structure a so-called well board having an opening or well of substantially the size of the photograph in which the photograph is received and which is overlapped by the frame member proper which has a sight opening therein smaller than the well opening.

Examples of such a structure are found in my Patents 2,092,348 and 2,181,874. An important advantage of frame mounts constructed in accordance with the present invention is the possibility of eliminating the well board while means are provided for positioning the picture and preventing it from slipping out of alignment with the sight opening.

Referring to Figs. 1 and 2, the frame there shown comprises a body board 10 on which is superposed a front board 12 having the sight opening 14 therethrough and behind the margins of which the picture is positioned. The front board 12 is of the same width but of lesser height than the back board providing exposed panels 16 and 18 at the top and bottom of the latter which panels are formed by the projecting portions of the back board 10. Because of the provision of the sight opening 14 in board 12, the latter has the form of a rectangular frame, the upper and lower cross elements of which appear in section in Fig. 2. Flexible sheet material 20, such as leatherette paper, covers and is adhesively secured to the entire exposed front face of the front board 12 and of the panels 16 and 18, thus confining the otherwise loose front board 12 closely against the body board 10, the two boards presenting along the margins of the front board closed joints at the top and bottom and open joints along the side, which latter joints open to the interstitial space between the opposed faces of the body board 10 and the rectangular frame formed by the front board 12, which space surrounds the sight opening 14 as is indicated in Figs. 2 and 2a by the heavy line. Through the open joints at the sides the photograph or similar thin sheet may easily be slid to lie beneath the front board exposed for view through the opening 14. The covering material 20 where it closes the joint between the lower margin of the front board and the panel 18 at the bottom holds the bottom bar of the frame formed by the front board pressed closely against the back board so as to pinch the lower edge of the picture, thus preventing it from slipping down and maintaining its position.

The edges of the mount may have any desired contour. I have here illustrated an ornamental top contour of the panel 16 formed by the upper part of the body board 10 and covered on its exposed front face by the leatherette 20 which might represent a portion of a figure or design on panel 16. The panels 16 and 18 may be of any desired width to receive printing or to provide for the attachment of such articles as a

calendar pad or the like and printing or other ornamentation of any desired character may be applied to the front of the mount.

An important advantage of the structure described is the fact that it may be made by means of the method which I will describe in connection with Fig. 3. To permit mounts as shown in Figs. 1 and 2 to be produced rapidly and economically in multiple, there may be provided a strip 100 of body board of a convenient length corresponding to the width of a plurality of finished mounts on which may be superposed a strip of board 120 from which the front boards 12 are to be formed, which strip 120 is narrower than the strip 100 and located between its edges. The strip 120 may be imperforate at this stage. For convenience in handling, the strip 120 may be glued to the strip 100 along a narrow zone 121 at either end, this portion in the lay-out illustrated being cut away as waste as will hereinafter appear. A strip 200 of flexible material may be coated with glue and pressed upon the face of the assemblage, as by passing the same through a bookbinder's wringer. The compound strip illustrated at the left of Fig. 3 may then be severed transversely along the transverse dot and dash lines shown to form a plurality of mounts. I have illustrated at the extreme right a zone 121 cut away as waste and a complete mount immediately to the left of the same as if it had been severed from the strip and moved somewhat to the right. In practice the transverse cuts may be made simultaneously by a gang operation, if desired. The cut may also form the ornamental margin, as indicated by the full line at the top of the severed mount at the right of the figure and the openings 14 may be cut through the hitherto imperforate strip 120 by means of suitable cutting dies, the stroke of which is so regulated that they do not sever the strip 100 beneath.

It is to be noted that in the preceding description the strips have been designated by a number corresponding to the number applied in Figs. 1 and 2 to the parts which are produced from these strips with an added zero.

By this method the mounts are very quickly and inexpensively produced, the covering 20 is accurately and neatly applied over the exposed surfaces, and the mounts may be made of desired contour, as exemplified by the irregular line at the top of Fig. 1 and at the right in Fig. 3. Hitherto in covering individual mounts with leatherette or the like the margins have been turned over and overlapped along the four sides, a costly operation dispensed with in the present invention.

Obviously the body board could be covered with flexible material in a similar manner. In Fig. 4 I have illustrated a mount with an additional back board 22 applied thereto which is secured to the front board by an extension of the covering material 20 thereover, which, however, is folded over at the top and the bottom only and by a simple fold, there being no necessity of forming a folded corner. The edges of the covering sheet may be butted or overlapped along the back, but in order not to complicate the drawing I have not attempted to show these edges in Fig. 4 or in Fig. 6 hereinafter. I have illustrated an easel 24 and a support 26 therefor, such as are shown in my Patent No. 2,240,209, formed from this back board 22 each by a cut which does not form a closed figure as in the case of the rectangle which forms the sight opening 14 but

on the contrary has its ends spaced to leave a part of the back board and its covering unsevered (along the upper margin of the parts 24 and 26, viewing Fig. 7) to act as a hinge. The construction as shown in Fig. 4 might be made as indicated in Fig. 3 by the addition of an additional strip to provide material for the back board 22 although a construction wherein the back board 22 of the same area as the body board 10 is secured by the covering material 20 implies substantially straight edges at the top and bottom of the mount around which the covering material may be folded.

In Fig. 5 I have illustrated a method of construction differing slightly from that of Fig. 3 and one wherein there may be utilized a strip to form back boards, the resultant mounts, however, differing somewhat from the one illustrated in Fig. 4. In the construction shown in Fig. 5 I utilize a body-forming strip 100 of a width sufficient to permit more than one mount of desired height, herein two, to be cut therefrom in transverse alignment. The material for the front board 12 is superposed on the body strip 100 to provide exposed margins 160 and one or more exposed intermediate longitudinal zones such as 180. Preferably this material takes the form of a strip 120 cut away along its margins and slotted along longitudinal zones, as illustrated in full lines at the left of Fig. 5, and by this construction there is provided a marginal end portion 121 of full width which is convenient in correctly assembling the strips 100 and 120 and along which they may be glued together for convenience in handling as in the case of the strips in Fig. 3. The covering material 200 may be applied as in the case of Fig. 3 and the strip severed, but not only along the transverse lines but also lengthwise along the longitudinal zone 180 so that from each transverse section of the strip in the example illustrated two frames are formed, the openings 14 being cut as before.

If in Fig. 5 the longitudinal cut were omitted, the resultant transverse segment of the strip would serve as an example of a mount having more than one sight opening, constructed to maintain a picture or like sheet in position relative to each opening without danger of slipping.

In order to provide a back board 22 in a construction such as is illustrated at the right of Fig. 5, a strip or strips 220 of back-board-forming material may be superposed on the back of the body strip 120 in such a manner as to expose a zone thereof corresponding to the zone 180 on the front face, as is best illustrated in Fig. 6. The back-board-forming material 220 is then secured by the folded-over covering material 200 along the outer edges and, at the location of the zone 180, by the extension of the covering material past the edge of the strip into adhesive contact with the exposed face of the body board at the zone 180. In the severed mount as illustrated by the rear view, Fig. 7, the edge of the back board which in the blank of Figs. 5 and 6 lies adjacent the zone 180 is spaced from that edge of the body board which is formed by the longitudinal cut in Fig. 5, and which in Fig. 7 is the top edge, and these parts are united along this top edge of the back board by the overlying covering material 20. An easel 24 may be cut from the back board 22 as in the case of Fig. 4 or cuts may be made adjacent the edge of the back board intersecting such edge, for instance, to sever a portion 28 of the back board which, however, will remain secured to the structure by

the covering material 20 adherent thereto which provides a hinged joint therefor. In Fig. 7 this part 28 is illustrated as a suspending tab. I make no claim in the present application to arrangements such as exemplified by this part 28 as claims thereto are more appropriately included in my copending application, Serial No. 461,983, to which reference is hereby made.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A picture mount comprising a body board, an apertured board loosely superposed thereon to define between the opposed faces of the boards an interstitial space surrounding the aperture, at least the lower edge of the apertured board being spaced above the lower edge of the body board to expose an extended area of the latter, and a covering of sheet material securing the boards together secured to the front of the apertured board and extending across the lower edge thereof and secured to the face of the aforementioned area to provide a sealed joint at the said lower edge of the apertured board maintaining it firmly against the underlying face of the body board to position the lower edge of a picture the margins of which are received in the interstitial space.

2. A picture mount comprising a body board, an apertured board loosely superposed thereon to define between the opposed faces of the boards an interstitial space surrounding the aperture, at least the lower edge of the apertured board being spaced above the lower edge of the body board to expose an extended area of the latter, and a covering of sheet material over the entire front face of the structure secured to the front of the apertured board and extending across the lower edge thereof and secured to the face of the aforementioned area to provide a sealed joint at the said lower edge of the apertured board maintaining it firmly against the underlying face of the body board to position the lower edge of a picture the margins of which are received in the interstitial space, the covering terminating at a side edge of the apertured board to provide an open joint through which the picture may be inserted into said space.

3. A picture mount comprising a body board, an apertured board loosely superposed thereon to define between the opposed faces of the boards an interstitial space surrounding the aperture, at least the lower edge of the apertured board being spaced above the lower edge of the body board to expose an extended area of the latter, and a covering of sheet material securing the boards together secured to the front of the apertured board and extending across the lower edge thereof and secured to the face of the aforementioned area to provide a sealed joint at the said lower edge of the apertured board maintaining it firmly against the underlying face of the body board to position the lower edge of a picture the margins of which are received in the interstitial space, the structure presenting a slit off from the face thereof providing for insertion of the picture into such interstitial space.

4. A picture mount comprising a body board,

an apertured board of like width and lesser height loosely superposed thereon flush with the side edges and spaced from at least one of the end edges thereof and defining therewith an interstitial space surrounding the aperture, and a covering of sheet material overlying said apertured board and the face of the body board where it extends beyond the same and adhesively secured thereto to join them, said covering terminating at the margins of the aperture and at the side edges.

5. A picture mount comprising a body board, an apertured board loosely superposed thereon to define between the opposed faces of the boards an interstitial space surrounding the aperture, at least the lower edge of the apertured board being spaced above the lower edge of the body board to expose an extended area of the latter, and a covering of sheet material securing the boards together secured to the front of the apertured board and extending across the lower edge thereof and secured to the face of the aforementioned area to provide a sealed joint at the said lower edge of the apertured board maintaining it firmly against the underlying face of the body board to position the lower edge of a picture the margins of which are received in the interstitial space, the structure presenting a slit remote from said lower edge of the apertured board providing for the insertion of the picture into such interstitial space.

6. A picture mount comprising a body board, an apertured board loosely superposed thereon to define between the opposed faces of the boards an interstitial space surrounding the aperture, the upper and lower edges of the apertured board being spaced from the corresponding edge of the back board to expose substantial areas of the back board above and below the apertured board, and a covering of sheet material of no greater area than the body board superposed on the front face of the boards, secured to the front face of the apertured board, extending past the upper and lower edges thereof and secured to said areas.

7. A method of forming picture mounts comprising superposing on a relatively wide strip of board a strip of board relatively narrow throughout at least a greater portion of its length, adhesively securing to the exposed upper faces a strip of flexible sheet material wider at least than the narrow strip, dividing the strips transversely into a plurality of mounts and cutting sight openings through the narrow strip and the sheet material covering the same.

8. A method of forming picture mounts comprising superposing on a relatively wide strip of board a strip of board relatively narrow throughout at least a greater portion of its length and securing them together by attachment in zones of restricted length longitudinal thereof, adhesively securing to the exposed upper faces a strip of flexible sheet material wider at least than the narrow strip, dividing the strip transversely into a plurality of mounts by cuts remote from said zones to provide in the cut sections open joints between the boards, and cutting sight openings in one of said strips between the lines of division and within the superposed areas of the strips from the one face of the assembly to the plane between the strips.

9. A method of forming picture mounts comprising superposing on a relatively wide body strip of board a front strip of board relatively narrow throughout at least the greater portion of its length and a back strip, securing them

together by adhesively securing a strip of flexible material to the exposed front faces and by folding over marginal portions of the strip and adhesively securing them to the back strip, and cutting mount-forming sections from the assembly by cuts including transverse cuts providing in the resultant sections open joints between the front and body boards, and cutting sight openings through the narrow strip and the flexible material covering the same.

10. A method of forming picture mounts comprising superposing on a strip of board a second strip of board of such shape and dimensions as to leave the first strip exposed in at least the greater portion of the length of the assemblage along a margin and along a zone extending between the sides, securing the strips together by a strip of flexible sheet material adhesively united to the front face of said second strip and to the exposed surface of the first strip along said margin and zone, dividing the strip by transverse cuts and a longitudinal cut along such zone, and cutting sight openings in one of said strips between the lines of division and within the superposed areas of the strips from the one face of the assembly to the plane between the strips.

11. A method of forming picture mounts comprising superposing on a strip of board narrow strips of board in spaced relation to define an exposed longitudinal zone of the first board between them, securing them together by a strip of flexible sheet material adhesively united to the front face of said second strip and to the exposed surface of the first strip along said zone and anchored along the sides of the assemblage, dividing the strip by transverse cuts and a longitudinal cut along such zone, and cutting sight openings in one of said strips between the lines of division and within the superposed areas of the strips from the one face of the assembly to the plane between the strips.

12. A picture mount comprising a pair of boards loosely superposed one on another to define an interstitial space between the opposed faces thereof, one of the boards being of smaller area than the other and having at least its lower edge spaced above the lower edge of the larger board to expose an extended area of the latter, one of said boards having an aperture therethrough of lesser area than the smaller board and located within the periphery of the same to provide a framed opening, and means for securing the boards together comprising sheet material secured to the exposed face of the smaller board and extending across the lower edge thereof and secured to the face of the aforementioned extended area to provide a sealed joint at the said lower edge of the smaller board maintaining it firmly against the face of the larger board to position the lower edge of a picture the margins of which are received in said interstitial space in the region surrounding said aperture.

13. A picture mount comprising a pair of boards loosely superposed one on another to define an interstitial space between the opposed faces thereof, one of the boards being of smaller area than the other and having at least its lower edge spaced above the lower edge of the larger board to expose an extended area of the latter, one of said

boards having an aperture therethrough of lesser area than the smaller board and located within the periphery of the same to provide a framed opening, and means for securing the boards together comprising sheet material secured to the exposed face of the smaller board and extending across the lower edge thereof and secured to the face of the aforementioned extended area to provide a sealed joint at the said lower edge of the smaller board maintaining it firmly against the face of the larger board to position the lower edge of a picture the margins of which are received in said interstitial space in the region surrounding said aperture, the sheet material terminating at a side edge of the smaller board to provide an open joint through which the picture may be inserted into said space.

14. A picture mount comprising a pair of boards loosely superposed one on another to define an interstitial space between the opposed faces thereof, one of the boards being of smaller area than the other and having its upper and lower edges spaced from the corresponding edges of the larger board to expose substantial areas of the larger board above and below the same, one of the boards having an aperture therethrough of lesser area than the smaller board and located within the periphery of the same to define a framed opening, and means for securing the boards together comprising sheet material of no greater outer dimensions than the larger board superposed on the exposed face of the smaller board, extending past the upper and lower edges of said smaller board and secured to said exposed areas.

15. A method of forming picture mounts comprising superposing on a relatively wide strip of board a strip of board relatively narrow throughout at least a greater portion of its length, adhesively securing to the exposed upper faces a strip of flexible sheet material wider at least than the narrow strip, dividing the strip transversely into a plurality of mounts and cutting sight openings in one of said strips between the lines of division and within the superposed areas of the strips from the one face of the assembly to the plane between the strips.

16. A picture mount comprising a pair of boards loosely superposed one on another to define an interstitial space between the opposed faces thereof, one of the boards being of smaller area than the other and having at least one of its edges spaced from the corresponding edge of the larger board to expose an extended area of the latter, one of said boards having an aperture therethrough of lesser area than the smaller board and located within the periphery of the same to provide a framed opening, and means for securing the boards together comprising sheet material secured to the exposed face of the smaller board and extending across the said one edge thereof and secured to the face of the aforementioned area to provide a sealed joint at the said one edge of the smaller board maintaining it firmly against the face of the larger board to position the edge of a picture the margins of which are received in said interstitial space in the region surrounding said aperture.

CERTIFICATE OF CORRECTION.

Patent No. 2,369,438.

February 13, 1945.

CARROLL N. CROSS.

It is hereby certified that error appears in the printed specification of the above numbered patent requiring correction as follows: Page 4, second column, line 42, claim 15, for "strip" second occurrence read --strips-- and that the said Letters Patent should be read with this correction therei that the same may conform to the record of the case in the Patent Office.

Signed and sealed this 15th day of May, A. D. 1945.
